CHARLES D. DERBY, OF DAYTON, OHIO, ASSIGNOR TO THE JOYCE-GRIDLAND COMPANY, OF DAYTON, OHIO, A CORPORATION OF OHIO.

OPERATING MECHANISM FOR LIFTING-JACKS.

1,372,868.

Specification of Letters Patent. Patented Mar. 29, 1921.

Application filed March 12, 1920. Serial No. 365,173.

To all whom it may concern:

Be it known that I, CHARLES D. DERBY, a citizen of the United States, residing at Dayton, in the county of Montgomery and State of Ohio, have invented certain new and useful Improvements in Operating Mechanism for Lifting-Jacks, of which the following is a specification, reference being had therein to the accompanying drawing.

This invention relates to operating mechanism for lifting jacks and the like, and more particularly to what is known as a fine toothed ratchet mechanism.

One object of the invention is to provide a mechanism of this kind which will be simple in its construction and operation; and in which the pawl will engage the ratchet wheel with a strong gripping action and will have no tendency to slip.

A further object of the invention is to provide a mechanism of this kind which can be easily reversed by the manipulation of the lever and without the necessity of the operator crawling under or reaching under the load.

Other objects of the invention will appear as the mechanism is described in detail.

Figure 1 is a perspective view of a jack embodying my invention; Fig. 2 is a transverse sectional view taken through the ratchet wheel; and Fig. 3 is a side elevation of the ratchet mechanism.

In these drawings I have illustrated one embodiment of my invention and have shown the same as applied to a lifting jack of a well known construction and which is designed in the present case, as a truck jack. It will be understood, however, that this embodiment of the invention has been chosen for the purpose of illustration only and that the invention may be applied to jacks of various kinds, or to other devices, in which a ratchet mechanism may be employed.

As here illustrated, the jack comprises a base 1 having mounted therein a screw 2 in which is mounted a second screw 3 to the upper end of which is secured the cap, or load engaging member, 4. The telescoping screws 2 and 3 constitute the lifting member of the jack and are threaded in opposite directions so that the rotation of the outer screw 2 will not only cause this screw to be moved lengthwise of the base 1 but will also cause the inner screw 3 to be moved length-

wise relatively to the outer screw. Rotatory movement is imparted to the outer screw by means of a suitable actuating member, such as a ratchet wheel 5 which is rigidly secured to the upper end thereof and which in the present instance is provided with radial teeth which are of a V-shape. Rotatably mounted for movement about the axis of the ratchet wheel is a lever supporting structure which, as here shown, comprises two plates 6 and 7 arranged respectively above and below the ratchet wheel. These plates are preferably rigidly connected one to the other and in the present instance they are united by a semi-circular flange 8 which is formed integral therewith and extends about approximately one half of the ratchet wheel. The plates and flange thus constitute a housing inclosing the ratchet wheel but open along one edge to expose the teeth of the ratchet wheel for engagement by the pawl. The plates 6 and 7 are provided with outwardly extending portions 9 to receive between them the end portion of a lever 10, which preferably comprises a socket portion adapted to receive a bar, or spike, 11. Rigidly secured to the lever and extending in opposite directions therefrom along the edge of the actuating member are two projections or pawls 12 and 13 each having near its outer end a portion adapted to be moved into and out of operative engagement with the actuating member by the manipulation of the lever. When the actuating member is in the form of a ratchet wheel the pawl may be provided with teeth and, in the present instance, each pawl is shown as having a series of V-shaped teeth adapted to mesh with the teeth of the ratchet wheel. The pawls 12 and 13 are of such length and are so arranged with relation to the lever that when the lever is moved about its axis the pawl on that side toward which the lever is moved will be moved in a substantially radial direction into engagement with the teeth of the ratchet wheel, thus causing the teeth of the pawl to be seated firmly in the recesses between the teeth of the ratchet wheel and to engage the same with a gripping action, which will effectually prevent any slipping of the pawls relatively to the ratchet wheel. It will be apparent that when the lever is actuated it will first move about the axis of its pivotal connection to the supporting structure 110

structure to cause the pawl on that side thereof toward which it is moved to engage the teeth of the ratchet wheel and that after this engagement has been established, 5 the continued movement of the lever will cause the supporting structure and the ratchet wheel to rotate thus actuating the lifting member. Upon the return movement of the lever it will be first moved about the 10 axis of its pivotal connection to the supporting structure to disengage the pawl from the ratchet wheel and the further movement thereof will rotate the supporting structure relatively to the ratchet wheel to permit the 15 lever, and the pawl to be returned to their initial positions. Means are provided to so limit the pivotal movement of the lever in a return direction that the pawl on the opposite side thereof will not be moved into 20 engagement with the ratchet wheel but will be held in a neutral position while return movement is imparted to the lever and to the supporting structure. To this end I have mounted on the supporting structure a 25 stop 14 arranged in the path of a dog 15 mounted upon the lever and so arranged that when the lever has been moved to substantially a central position with relation to the supporting structure, the dog will engage 30 the stop and check the pivotal movement of the lever. The dog is preferably yieldable so that it can be moved across the stop to permit the mechanism to be reversed, to move the lifting member in the opposite 35 direction. In order that the lever may assume its central, or neutral, position when the dog 15 is located on either side of the stop 14 I have pivotally mounted the stop, as shown at 16, and have provided the same 40 with oppositely extending projections 17 and 18 arranged to engage the opposite sides of a fixed stop 19 on the supporting structure, this fixed stop comprising, in the present instance, the head of a bolt 20 by means 45 of which the lever is pivotally connected with the supporting structure. The projections 17 and 18 on the movable stop 14 are so arranged with relation to the fixed stop 19 that the movable stop will have a limited 50 pivotal movement, which is sufficient to position the same on either side of a central line, that is, a line extending through the axis of the ratchet wheel and through the axis of the lever. The arrangement of the 55 movable stop is also such as to permit this stop to move with the lever until the pawl has engaged the ratchet wheel, as shown in Fig. 2. Upon the return movement of the lever, from the position shown in full lines 60 in Fig. 2, the stop will move about its axis 16 until the projection 17 engages the fixed stop 19 and thus checks the pivotal movement of the lever and causes the supporting structure to move therewith. When it is 65 desired to reverse the operation of the jack

this may be accomplished by applying sufficient force to the lever to cause the pawl 15 to yield and ride over the end of the movable stop 14. This may be quickly and easily accomplished by a jerk on the end of 70 the lever, thus avoiding any necessity for the operator crawling under, or reaching under, the load.

The operation of the mechanism will be readily understood from the foregoing description and it will be apparent that I have provided an operating mechanism which is very simple both in its construction and operation, which is of a very strong, durable character, in which the pawls will 75 engage the ratchet wheel in such a manner as to establish a firm connection between the same, and in which the teeth of the pawls will have no tendency to slip or ride over the teeth of the ratchet wheel, this being 80 due to the fact that the pressure on the teeth is approximately radial to the ratchet wheel and the teeth of the pawl are caused to engage the teeth of the ratchet wheel with a wedging action. Further it will be apparent 85 that the operating mechanism may be very quickly and easily reversed from a point remote from the jack.

While I have shown and described one embodiment of my invention I wish it to be 90 understood that I do not desire to be limited to the details thereof as various modifications may occur to a person skilled in the art.

Having now fully described my invention 100 what I claim as new and desire to secure by Letters Patent is:

1. In a lifting jack, a lifting member, a ratchet wheel operatively connected therewith, a lever supporting structure mounted 105 for rotation about the axis of said ratchet wheel, a lever pivotally mounted on said structure, pawls carried by said lever and extending in opposite directions therefrom about said ratchet wheel and so arranged 110 that the movement of said lever about its axis will cause that pawl toward which the lever is moved to engage said ratchet wheel, and means to limit the return movement of said lever about its pivotal connection to 115 said supporting structure, said means being reversible by the manipulation of said lever to enable the movement of said lever to be limited in either direction.

2. In a lifting jack, a lifting member, a ratchet wheel operatively connected therewith, a lever supporting structure mounted 120 for rotation about the axis of said ratchet wheel, a lever pivotally mounted on said structure, pawls carried by said lever and extending in opposite directions therefrom about said ratchet wheel and so arranged 125 that the movement of said lever about its axis will cause that pawl toward which the lever is moved to engage said ratchet wheel, 130

and coöperating stops carried by said lever and said supporting structure to limit the return movement of said lever about its pivotal connection to said supporting structure, one of said stops being yieldable to permit it to pass the other stop and to reverse the operation of the jack.

3. In a lifting jack, a lifting member, a ratchet wheel operatively connected therewith, a lever supporting structure mounted for rotation about the axis of said ratchet wheel, a lever pivotally mounted on said structure, pawls carried by said lever and extending in opposite directions therefrom about said ratchet wheel and so arranged that the movement of said lever about its axis will cause that pawl toward which the lever is moved to engage said ratchet wheel, a stop mounted on said supporting structure for a limited pivotal movement, and a dog yieldably mounted on said lever and arranged to coöperate with said stop to limit the movement of said lever in one direction about its pivotal connection with said supporting structure.

4. In a lifting jack, a lifting member, a ratchet wheel operatively connected therewith, a lever supporting structure mounted for rotation about the axis of said ratchet wheel, a lever pivotally mounted on said structure, pawls rigidly secured to said lever and extending in opposite directions therefrom about said ratchet wheel and so arranged that the movement of said lever about its axis will cause that pawl toward which the lever is moved to engage said ratchet wheel, a dog yieldably mounted on said lever, a stop pivotally mounted on said supporting structure and having a part arranged to coöperate with said dog to limit the movement of said lever in one direction about its pivotal connection with said supporting structure, said movable stop having oppositely extending projections, and a fixed stop carried by said supporting structure and arranged between the projections of said movable stop to limit the pivotal movement of the latter.

5. In a lifting jack, a lifting member, a ratchet wheel operatively connected therewith, a lever supporting structure mounted for rotation about the axis of said ratchet wheel, a lever pivotally mounted on said structure, pawls rigidly secured to said lever and extending in opposite directions therefrom about said ratchet wheel and so arranged that the movement of said lever about its axis will cause that pawl toward which the lever is moved to engage said ratchet wheel, and coöperating stops carried respectively by said lever and said supporting structure to limit the movement of said lever in one direction about its pivotal connection with said supporting structure, one of said stops being of such a character that the rela-

tive positions of the two stops can be reversed by the manipulation of said lever.

6. In a lifting jack, a lifting member, a ratchet wheel operatively connected therewith, a lever supporting structure mounted for rotation about the axis of said ratchet wheel and comprising upper and lower members, a lever having a part extending between the upper and lower members of said supporting structure and pivotally connected therewith, said lever also having pawls formed integral therewith and extending in opposite directions therefrom about said ratchet wheel, a dog yieldably mounted on said lever, and a stop mounted on said structure to coöperate with said dog and having a limited pivotal movement to permit it to be positioned on either side of said dog when said lever is in a neutral position.

7. In a lifting jack, a lifting member, an actuating member operatively connected with said lifting member, a lever supporting structure mounted for rotation about the axis of said actuating member, a lever pivotally mounted on said structure, and pawls rigidly secured to said lever and extending laterally therefrom in different directions, each pawl having a portion arranged to be moved into and out of gripping engagement with said actuating member by the movement of said lever about its axis, and means to limit the return movement of said lever, said means being reversible by the manipulation of said lever.

8. In a lifting jack, a lifting member, an actuating member operatively connected with said lifting member, a lever supporting structure mounted for rotation about the axis of said actuating member, a lever pivotally mounted on said structure, pawls secured to said lever and extending laterally therefrom in different directions, each pawl having a portion arranged to be moved into and out of gripping engagement with said actuating member by the movement of said lever about its axis, and coöoperating stops to limit the return movement of said lever about its pivotal connection to said supporting structure, one of said stops being reversible to engage either side of the other stop and said other stop being adjustable relatively to the reversible stop.

9. In a lifting jack, a lifting member, an actuating member operatively connected with said lifting member, a lever supporting structure mounted for rotation about the axis of said actuating member, a lever pivotally mounted on said structure, pawls secured to said lever and extending laterally therefrom in different directions, each pawl having a portion arranged to be moved into and out of gripping engagement with said actuating member by the movement of said lever about its axis, a stop pivotally mounted on said lever supporting structure, means to limit

the pivotal movement of said stop, and a reversible stop carried by said lever and adapted to engage either side of said pivoted stop.

10. In a lifting jack, a lifting member, an actuating member operatively connected with said lifting member, a lever supporting structure mounted for rotation about the axis of said actuating member, a lever pivotally mounted on said structure, pawls secured to 10 said lever and extending laterally therefrom in different directions, each pawl having a portion arranged to be moved into and out of gripping engagement with said actuating member by the movement of said lever about 15 its axis, a stop mounted on said lever supporting structure, a second stop pivotally mounted on said lever supporting structure and having parts arranged on the opposite sides of the first mentioned stop to limit the 20 movement of said pivoted stop, and a yieldable stop carried by said lever and adapted to engage either side of said pivoted stop.

11. In a lifting jack, a lifting member, an actuating member operatively connected with said lifting member, a lever supporting 25 structure mounted for rotation about the axis of said actuating member, a lever pivotally mounted on said structure, and pawls rigidly secured to said lever and extending laterally therefrom in different directions, each pawl 30 having a portion arranged to be moved into and out of gripping engagement with said actuating member by the movement of said lever about its axis, and coöperating stops carried by said lever and said supporting 35 structure, respectively, to limit the return movement of said lever about its pivotal connection to said supporting structure, one of said stops being yieldable to permit it to pass the other stop and to reverse the opera- 40 tion of the jack.

In testimony whereof, I affix my signature hereto.

CHARLES D. DERBY.
